UNITED STATES PATENT OFFICE.

HARRY A. KNAUSS, OF BROOKLYN, NEW YORK, ASSIGNOR, BY DIRECT AND MESNE ASSIGNMENTS, OF ONE-THIRD TO EDWARD M. EVARTS, OF NEW YORK, N. Y., AND ONE-THIRD TO FRANK V. KNAUSS, OF PORTSMOUTH, OHIO.

METHOD OF AND MEANS FOR RECORDING AND RESULTING PRODUCTS.

Application filed April 14, 1923. Serial No. 633,698.

My present invention relates to methods of making records, whether of light, sound or other character, or for printing or other purposes, and also to the means for making such records and to the resulting products. It is an object of the present invention to devise methods and means of the general character referred to by which I shall be enabled to prepare the resulting products, in the form of light, sound or other records, or in the form of plates for printing or for any other desired purpose, in a simple, economical and very expeditious manner. In this way I am enabled to effect considerable economies in time, labor and material which have hitherto been necessary for the fabrication of such records. While not limited thereto, my invention finds particularly successful application in connection with the fabrication of masters and stampers for making sound records, particularly of the disk phonograph type, and in the fabrication of copper plates for half-tone or other printing purposes. The principles of the present invention may also be applied with considerable success for detecting and measuring flaws in substances opaque to light.

In the accompanying specification I shall describe several illustrative embodiments of the method, means and resulting products of the present invention. It is, however, to be clearly understood that my invention is not limited to the illustrative embodiments thereof herein shown and described for purposes of illustration only.

In the accompanying drawing, wherein I have more or less diagrammatically illustrated one manner of carrying out one form of the method of the present invention, including also several types of means which may be employed for this purpose and several embodiments of the resulting product, as applied more particularly to the fabrication of stampers for sound records preferably of the disk phonograph type;

Fig. 1 is a cross section of a radio-lucent wax master of the "lateral cut" type;

Fig. 2 is a cross section of the wax master shown in Fig. 1, with the groove or grooves therein filled with a radio-opaque substance,

in accordance with the principles of the present invention;

Fig. 3 is a cross section of the radio-lucent wax master shown in Fig. 2, with the radio-opaque substance filling the groove or grooves thereof and with a protecting member applied thereto so as to protect and maintain the radio-opaque substance in place within the groove or grooves of the wax master;

Fig. 4 is a cross section of the same after the thickness of the master has been substantially reduced for the purpose of the present invention;

Fig. 5 is a diagrammatical view, partly in cross section and partly in elevation, showing one way of using the wax master shown in Figs. 3 or 4 for the production of a radiograph;

Fig. 6 is a plan view of the resulting radiograph obtained by using the wax master shown in Figs. 1, 2, 3 and 4;

Fig. 7 is a cross section of a wax master of the "hill and dale" type of groove; and

Fig. 8 is a plan view of a radiograph obtained by using the type of master illustrated in Fig. 7.

Before describing in detail the aforesaid illustrative embodiment of the present invention, it may be desirable briefly to point out the disadvantages inherent in the methods, means, and resulting products hitherto employed and obtained in the art to which the present invention relates. Taking, for example, the art of making masters or stampers for phonograph records, as of metal, such as copper, by the methods hitherto practiced, this being an example of one of the many fields to which the principles of the present invention are more particularly applicable, it may be pointed out that in the fabrication of such masters and stampers in accordance with the prior practice, the original wax masters had first to be very carefully treated with a conducting substance,

such as finely ground graphite or copper dust, to render the same conductive. A copper mother was then made from the wax master by electrodeposition, this being a very slow and tedious process consuming

60

many hours, due to the necessity of operating at low temperatures and correspondingly low current densities and low rates of deposition of the copper, in order to prevent the 5 wax master from being too highly heated, which would cause it to soften and lose its shape, and thus damage the accuracy of the lines of the record groove.

After the copper mother had been thus prepared, the same had to be sulphided, nickelized or given some other treatment, generally harmful to the accuracy of the record groove, in order to enable the same to receive a separable deposit of copper or other 10 metal in the production of the copper or other metal masters. From these copper or other metal masters, of which a number might be, and generally were, made, by the same laborious and tedious method already 15 outlined for a production of a single one of such masters, a series of copper or other metal stampers would be made by treating the copper or other metal masters to sulphide, nickelize or otherwise act upon the 20 same to enable them to receive a separable deposit or coating of copper or other metal. From these stampers the records of plastic material are then made.

When it is considered that in making 30 records, a matter of a single day's, or even several hours', delay is of great importance to enable the manufacturer of such records to place the same on the market, if possible, in advance of the time when his competitors 35 may place records of the same musical or other composition on the market, and when it is further considered that by the laborious methods hitherto employed days might elapse before a substantial quantity of completed 40 records could be put on the market from the time the original recording in wax was made, it becomes readily apparent what important commercial and technical advantages would result from the discovery of 45 new methods and means enabling the necessary stampers and resulting records to be made in a few hours rather than in a few days.

Such desirable results are accomplished in 50 a simple and ingenuous way by the method and means of the present invention, which at the same time results in a much superior stamper, since the lines of the record groove are subject to less mutilation than results 55 from the methods hitherto employed for making such stampers. In fact, the lines of the record groove of a stamper made in accordance with the principles of the present invention, in the illustrative example now 60 being described, where the invention is applied for this particular purpose, out of the many uses to which it may be put, is hardly changed or altered in any way from the original form which it has in the wax master 65 and is, in fact, a substantially identical re-

production or facimile of the record groove of the wax master. At the same time, by means of the present invention, I avoid the tedious and expensive delays and the laborious technique hitherto employed in the fabrication of stampers in accordance with the practice hitherto obtaining in this particular art. It may be seen that the picture usually appearing in the center of the ordinary type of sound record may be embodied in the 75 original wax master and thus in the resulting stamper. In fact, pictures may be recorded and transmitted in accordance with the principles of the present invention, as more fully described and claimed in another 80 of my applications.

It is to be understood, of course, that similar advantages in technique and equivalent economies in time, labor and material are effected by the application of the principles 85 of the present invention to the other arts where the same may be employed with advantage, as in the production of molds and dies for plastic or other materials, in the preparation and reproduction of half-tone 90 or other printing plates, metal indices, name plates, etc., and in any other of the arts where a reproducing surface is desired to be prepared.

Referring now to the aforesaid illustrative 95 embodiments of the present invention which are herein shown and described merely for the purpose of exemplifying a few of the many forms of applying the principles of the present invention, 10 indicates a wax 10 master of the "lateral cut" disk type, such as is used in connection with the "Victor" and "Columbia" phonographs. The master 10 consists of a comparatively thick body of some radio-lucent material, such as phonograph recording wax, without the addition of aluminum or other metal compounds, or of paraffin or beeswax of the proper quality and consistency. This material, while opaque to light, is translucent to X-rays. 1 Such material, while being opaque to light, may in certain instances be lucent to light as well as lucent to X-rays.

The material 11, of which the wax master 10 is made, is opaque to common light, but 1 lucent to X-rays. Preferably the body portion 11 of which the wax master 10 is made has depressed portions therein. In the particular example given, these depressed portions are provided by the record groove 12 1 which, as already stated, is of the "lateral cut" type of groove, being substantially in the form of a spiral of uniform depth varying to either side of the main spiral path, in accordance with the particular sounds or other impulses recorded and the amplitudes of the vibration of such sounds or other impulses.

I now apply to the upper or record surface of the wax master 10, a radio-opaque

substance, that is, a substance which will not permit the passage of X-rays or equivalent rays therethrough, unlike the material 11 of which the wax master is made, which is radio-lucent and thus readily permits the passage therethrough of X-rays. While various materials may be employed for this purpose, I prefer to use finely ground barium sulphate powder as being a material 10 which is easy to obtain, is comparatively inexpensive, and serves the desired purpose admirably. I apply this material to the portions of the record body 11 which are of lesser thickness, as by applying such radio-15 opaque substance to the depressed portions of such body. In the particular instance given herein by way of illustration, I fill the groove or grooves 12 of the record body 11 with the radio-opaque substance 13. The 20 radio-opaque substance 13 should be applied to the groove or grooves 12 of the body 11 so as to substantially completely fill such grooves, so as to make the record body 11 of substantially the same total thickness at every 25 normal cross-section of the same all the way across its surface. Any excess of radio-opaque substance present on the top of the record surface of the record body 11 may be removed in any suitable manner, thus leaving 30 the groove or grooves 12 filled up to their upper edges, to a uniform depth, with no surplus radio opaque substance in the spaces between the grooves filled with such substance. It is, of course, apparent that 35 numerous variations of this method of manipulation may be employed with success, while still utilizing the principles of the present invention. For example, I may place a seal upon the record groove and inject a radio-opaque substance in paste form, 40 into the sealed spiral groove.

In order to protect the grooves containing the radio-opaque substance, I provide means for protecting said radio opaque-substance. 45 Preferably such protecting means is in the form of a protecting shield or other plate 14, which may be made of thin wax, applied in sheet, film, or plastic form, this wax being radio-lucent so as to interfere as little as possible with the passage therethrough of the X-rays or equivalent rays used subsequently in the present process. The plate or other protecting shield 14 is applied directly over the record surface of the body 11 50 and serves to keep the radio-opaque substance 13 firmly packed in the groove or grooves 12 so that the same cannot be dislodged from such groove or grooves in the subsequent manipulations of the body 11 in accordance with the method of the present 55 invention. The protecting plate or shield 14 may, for this purpose, be securely cemented or sealed into place by a suitable adhesive applied at the periphery thereof, such 60 adhesive being indicated by reference char-

acter 14', or in any other suitable and convenient manner.

In order to enable the more convenient and certain application of the principles of the present invention, I prefer to reduce the 70 thickness of the body of radio-lucent material 11 to a minimum, without endangering the retention and preservation of the accuracy of the record groove 12. For this purpose I may shave off a substantial portion 75 of the body 11 from the under side thereof by inverting the body 11 containing the radio-opaque substance 13 in the groove or grooves 12 thereof, this manipulation being feasible as a result of the provision of 80 the protecting shield or plate 14 which retains the radio-lucent material in place in the groove or grooves 12. Any suitable shaving machine, such as those customarily employed in the art at the present time for 85 similar purposes, may then be used for the purpose of removing excess material from the bottom of the record body 11.

I now proceed to prepare a radiograph, 90 that is, a radiographic or X-ray negative, preferably in film form, of the record groove 12. The purpose of this is to obtain, by the use of X-rays or equivalent rays directly permeating or penetrating the radio-lucent body 11, which body, as already described, 95 is opaque to ordinary light and which is now preferably of reduced thickness, and the radio-lucent film or plate 14, and particularly those portions of the radio-lucent bodies 11 and 14 which lie between the 100 groove or grooves 12 filled with radio-opaque material 13, a radiograph or radiographic line radiograph, such as a film negative or radiograph, or accurate radiographic record or picture of the groove or grooves 105 12. This desirable and highly novel result follows from the fact that the groove or grooves 12 have been accurately filled up to the edges of such groove or grooves with the radio-opaque material 13. There is, accordingly, produced on the X-ray plate or film 15, a line radiograph of the groove or grooves 12 which, in the particular instance now being described, is in the form of a laterally fluctuating spiral path 16 on the 110 plate or film 15, as shown more clearly in Fig. 6 of the drawing. As a source of X-rays, I may use any desirable type of X-ray or other vacuum tube 17, or any emanations having the power of penetrating 115 objects opaque to ordinary light, such as the various emanations, as shown in Fig. 5 of the drawing. The copper emulsion may be directly exposed to X-rays, as through the 120 wax master.

From the radiograph or radiographic line negative or other negative obtained as above set forth, I prepare a copper or zinc etching by the usual "half-tone" or copper or zinc 125 etching process. For this purpose the X-ray 130

film or radiograph is developed and fixed in the usual manner, which gives a clear black and white spiral negative or picture of the groove in the original sound record. 5 This negative may then be placed directly over a wet plate and the wet plate in turn transferred to the sensitized copper which is exposed to any desirable and suitable source of light, or to ultra-violet light, and 10 is then etched in accordance with the procedure well known to those skilled in the art to which the present invention relates.

The resulting copper etching, depending on whether it is a positive or negative, the 15 former yielding a depressed groove and the latter an elevated groove or ridge, may be directly used as a sound record and played, for which purpose the tone arm may be moved over the record surface by any suitable lathe mechanism, preferably the same lathe mechanism, or an equivalent mechanism synchronized with and similar to the lathe mechanism, which cut the sound groove in the original wax master. If desired, however, this copper record may be 20 nickelized and copper stampers prepared from the same, which may be done in a very short while, all as well known to those skilled in the art to which the present invention relates. These stampers may then be used for making the usual sound records of composition, in the manner now commonly employed for this purpose.

The advantages of the foregoing embodiments of the method and means of the 35 present invention are numerous and of great practical importance. By means of the present invention, the whole process of making the original copper etched record, including the steps of filling in the grooves in the wax master, applying the protecting covering to the same, shaving the bottom of the wax master down to the desired thickness, mounting the master so prepared on 40 the X-ray film in its lightproof envelope, exposing the master to the X-rays, developing and fixing the resulting X-ray negative, and finally preparing the copper etching from the radiograph or X-ray negative, 45 need not take over a half an hour, and may be done automatically, in one machine, as compared with the very considerable length of time, amounting often to twenty-four 50 hours, or longer, hitherto needed for producing a copper mother from which stampers might be made in accordance with the practice hitherto prevailing in the art to which the present invention relates.

The copper record made in accordance 55 with the process and employing the means of the present invention is much more accurate than the copper mother resulting from the methods hitherto employed for producing the same. Since the radiograph or X-ray negative or equivalent radiograph

of the groove in the wax master is an absolutely accurate black and white picture of such groove and may, by obvious expedients, be indefinitely absolutely accurately reproduced, enlarged or diminished, any desired 70 number of copper etched records or their equivalents may be made, all of equally absolute accuracy. From these any number of copper masters may quickly be produced, thus enabling the production of composition 75 or similar moulded records to be made from such stampers with a remarkable saving of time, labor and material.

In Figs. 7 and 8 of the drawing I have more or less diagrammatically indicated the 80 application of the principles of the present invention to a wax master of the "hill and dale" type of groove, the master being indicated by reference character 100 and consisting of radio-lucent material 101 having in 85 the upper surface thereof a groove 102 of the "hill and dale" type which is of a substantially true spiral form, of substantially uniform width, but of varying depth, as clearly indicated in Fig. 7 of the drawing. 90 The resulting copper etched record is indicated by reference character 103, as more clearly shown in Fig. 8 of the drawing. This record may be prepared in the manner described in the previous portions of this 95 specification for the production of the "lateral cut" type of record. The advantages of the application of the method and means of the present invention to the production of the record 103 of the "hill and dale" type 100 are the same as those set forth above for the "lateral cut" type of record and need not therefore be further enlarged upon here.

It may here be stated that the term "depression", or its equivalent, as used in the 105 specification and claims, is intended also to designate, wherever such meanings are acceptable, cavities or hollows, whether open to the exterior or entirely closed or sealed, such, for example, as tooth cavities or air 110 bubbles or other hollows or flaws in gems, metals and the like. It may also be stated here that the term "record", as used in the specification and claims, is intended also to 115 designate, wherever such a meaning is acceptable, records of the vibrations, pulsations or impulses of light, electricity, heat or other form or forms of energy, as well as of sound.

What I claim is:

1. The method of producing a record, 120 which comprises the steps of providing a record body with a record surface corresponding to varying wave impulses, and thereafter applying a radio-opaque substance to such record surface.

2. The method of producing a record, 125 which comprises the steps of providing a radio-lucent record body with a record surface corresponding to varying wave impulses, 130

and thereafter applying a radio-opaque substance to such record surface.

3. The method of producing a record, which comprises the steps of providing a record body with a record groove corresponding to varying wave impulses, and thereafter applying a radio-opaque substance to such record groove.

4. The method of producing a record, which comprises the steps of providing a radio-lucent record body with a record groove corresponding to varying wave impulses, and thereafter applying a radio-opaque substance to such record groove.

15 5. The method of producing a record, which comprises the steps of providing a radio-lucent record body with a record surface corresponding to varying sound wave impulses, and thereafter applying a radio-opaque substance to such record surface.

20 6. The method of producing a record, which comprises the steps of providing a record body with a record surface corresponding to varying sound wave impulses, and thereafter applying a radio-opaque substance to such record surface.

25 7. The method of producing a record, which comprises the steps of providing a radio-lucent record body with a record groove corresponding to varying sound wave impulses, and thereafter applying a radio-opaque substance to such record groove.

30 8. The method of producing a record, which comprises the steps of providing a record body with a record groove corresponding to varying sound wave impulses, and thereafter applying a radio-opaque substance to such record groove.

35 9. The method of producing a record, which comprises the steps of providing a radio-lucent record body with a record groove corresponding to varying sound wave impulses, applying a radio-opaque substance to such record groove, and thereafter obtaining a radiograph of said body by means of X-rays.

40 10. The method of producing a record, which comprises the steps of providing a radio-lucent record body with a record surface corresponding to varying sound wave impulses, applying a radio-opaque substance to such record surface, and thereafter obtaining a radiograph of said body by means of X-rays.

45 55 11. The method of producing a record, which comprises the steps of providing a record body with a record groove corresponding to varying wave impulses, applying a radio-opaque substance to such record groove, and thereafter obtaining a radiograph of said body by means of X-rays.

60 65 12. The method of producing a record, which comprises the steps of providing a record body with a record surface corresponding to varying wave impulses, apply-

ing a radio-opaque substance to such record surface, and thereafter obtaining a radiograph of said body by means of X-rays.

13. The method of producing a record, which comprises the steps of providing a record body with a record groove corresponding to varying sound wave impulses, applying a radio-opaque substance to such record groove, and thereafter obtaining a radiograph of said body by means of X-rays. 70

14. The method of producing a record, which comprises the steps of providing a record body with a record surface corresponding to varying sound wave impulses, applying a radio-opaque substance to such record surface, and thereafter obtaining a radiograph of said body by means of X-rays. 80

15. The method of producing a record, which comprises the steps of providing a radio-lucent record body with a record groove corresponding to varying wave impulses, applying a radio-opaque substance to such record groove, and thereafter obtaining a radiograph of said body by means of X-rays. 85

16. The method of producing a record, which comprises the steps of providing a radio-lucent record body with a record surface corresponding to varying wave impulses, applying a radio-opaque substance to such record surface, and thereafter obtaining a radiograph of said body by means of X-rays. 90

17. The method of producing a record, which comprises the steps of applying a radio-opaque substance to the surface of a radio-lucent body of varying surface characteristics, corresponding to varying wave impulses obtaining a radiographic line negative of said body by means of X-rays, and thereafter preparing a body having a reproducing surface from said line negative. 100

18. The method of producing a record which comprises the steps of applying a radio-opaque substance to the surface of a radio-lucent record body having depressed portions therein, corresponding to varying wave impulses obtaining a radiographic line negative of said body by means of X-rays, and thereafter preparing a body having a reproducing surface from said line negative. 110

19. The method of producing a record, which comprises the steps of applying a radio-opaque substance to the surface of the portions of lesser thickness of a radio-lucent body of varying thickness, corresponding to varying wave impulses obtaining a radiographic line negative of said body by means of X-rays, and thereafter preparing a body having a reproducing surface from said line negative. 115

20. The method of producing a record, which comprises the steps of applying a radio-opaque substance to the groove or grooves of a radio-lucent record body having one or more grooves therein, corresponding 120

2. Means for preparing records by use of X-rays, comprising a radio-lucent body of varying surface characteristics corresponding to varying wave impulses and having a radio-opaque substance applied to the portions of lesser thickness. 70
3. Means for preparing records by the use of X-rays, comprising a radio-lucent body of varying thickness corresponding to varying wave impulses and having a radio-opaque substance applied to the portions of lesser thickness. 75
4. Means for preparing records by the use of X-rays, comprising a radio-lucent body having depressed portions therein corresponding to varying wave impulses and having a radio-opaque substance applied to the depressed portions thereof. 80
5. Means for preparing records by the use of X-rays comprising a radio-lucent grooved body corresponding to varying wave impulses and having a radio-opaque substance in the groove or grooves thereof. 85
6. Means for preparing records by the use of X-rays, comprising a radio-lucent grooved body corresponding to varying wave impulses and having a radio-opaque substance in the groove or grooves thereof, in combination with means for protecting said radio-opaque substance. 90
7. Means for preparing records by the use of X-rays, comprising a radio-lucent body having depressed portions therein corresponding to varying wave impulses and having a radio-opaque substance applied to the depressed portions thereof, in combination with means for protecting said radio-opaque substance. 95
8. Means for preparing records by the use of X-rays, comprising a radio-lucent body of varying thickness corresponding to varying wave impulses and having a radio-opaque substance applied to the portions of lesser thickness, in combination with means for protecting said radio-opaque substance. 100
9. Means for preparing records by the use of X-rays, comprising a radio-lucent body having depressed portions therein corresponding to varying wave impulses and having a radio-opaque substance applied thereto, in combination with a protecting shield for said radio-opaque substance. 115
10. Means for preparing records by the use of X-rays, comprising a radio-lucent body of varying surface characteristics corresponding to varying wave impulses and having a radio-opaque substance applied thereto. 120
11. Means for preparing records by the use of X-rays comprising a radio-lucent body having depressed portions therein corresponding to varying wave impulses and having a radio-opaque substance applied thereto. 125
12. Means for preparing records by the use of X-rays, comprising a radio-lucent body of varying surface characteristics corresponding to varying wave impulses and having a radio-opaque substance applied thereto. 130
13. Means for preparing records by the use of X-rays, comprising a radio-lucent body of varying thickness corresponding to varying wave impulses and having a radio-opaque substance applied to the portions of lesser thickness, in combination with a protecting shield for said radio-opaque substance. 135
14. Means for preparing records by the use of X-rays, comprising a radio-lucent body having depressed portions therein corresponding to varying wave impulses and having a radio-opaque substance applied thereto. 140
15. Means for preparing records by the use of X-rays, comprising a radio-lucent body of varying surface characteristics corresponding to varying wave impulses and having a radio-opaque substance applied thereto. 145
16. Means for preparing records by the use of X-rays, comprising a radio-lucent body of varying thickness corresponding to varying wave impulses and having a radio-opaque substance applied to the portions of lesser thickness, in combination with a protecting shield for said radio-opaque substance. 150
17. Means for preparing records by the use of X-rays comprising a radio-lucent body having depressed portions therein corresponding to varying wave impulses and having a radio-opaque substance applied thereto. 155
18. Means for preparing records by the use of X-rays, comprising a radio-lucent body of varying surface characteristics corresponding to varying wave impulses and having a radio-opaque substance applied thereto. 160
19. Means for preparing records by the use of X-rays, comprising a radio-lucent body of varying thickness corresponding to varying wave impulses and having a radio-opaque substance applied to the portions of lesser thickness, in combination with a protecting shield for said radio-opaque substance. 165
20. Means for preparing records by the use of X-rays, comprising a radio-lucent body having depressed portions therein corresponding to varying wave impulses and having a radio-opaque substance applied thereto. 170
21. The method of producing a record, which comprises the steps of applying a radio-opaque substance to the surface of a radio-lucent body of varying thickness, corresponding to varying wave impulses, causing X-rays to penetrate the body so treated to obtain a radiographic line negative of the same, and thereafter preparing a body having a metallic reproducing surface from said line negative. 175
22. The method of producing a record, which comprises the steps of applying a radio-opaque substance to the surface or interior of the depressed portions of a radio-lucent body of varying surface characteristics, corresponding to varying wave impulses causing X-rays to penetrate the body so treated to obtain a radiographic line negative of the same, and thereafter preparing a body having a metallic reproducing surface from said line negative. 180
23. The method of producing a record, which comprises the steps of applying a radio-opaque substance to the surface or interior of the depressed portions of a radio-lucent record body having depressed portions therein, corresponding to varying wave impulses causing X-rays to penetrate the body so treated to obtain a radiographic line negative of the same, and thereafter preparing a body having a metallic reproducing surface from said line negative. 185
24. The method of producing a record, which comprises the steps of filling the groove or grooves of a radio-lucent record body having one or more grooves therein with a radio-opaque substance, corresponding to varying wave impulses causing X-rays to penetrate the body so treated to obtain a radiographic line negative of the same, and thereafter preparing a body having a metallic reproducing surface from said line negative. 190
25. Means for preparing records by the use of X-rays, comprising a radio-lucent body of varying surface characteristics corresponding to varying wave impulses and having a radio-opaque substance applied thereto. 195
26. Means for preparing records by the use of X-rays, comprising a radio-lucent body of varying thickness corresponding to varying wave impulses and having a radio-opaque substance applied thereto. 200
27. Means for preparing records by the use of X-rays comprising a radio-lucent body having depressed portions therein corresponding to varying wave impulses and having a radio-opaque substance applied thereto. 205

thereto, in combination with means for retaining said radio-opaque substance in place on said body.

38. Means for preparing records by the use of X-rays, comprising a radio-lucent body of varying thickness corresponding to varying wave impulses and having a radio-

opaque substance applied thereto, in combination with means for retaining said radio-opaque substance in place on said body.

10

In testimony, whereof, I have signed my name to this specification this 30th day of March, 1923.

HARRY A. KNAUSS.
